UNITED STATES PATENT OFFICE

154,831

DESIGN FOR A TIE HOLDER

Carl A. Anderson, Cranston, R. I., assignor to Anderson Tool & Die Works, Inc., a corporation of Rhode Island

Application January 13, 1948, Serial No. 143,691

Term of patent 3½ years

(Cl. D17—10)

To all whom it may concern:

Be it known that I, Carl A. Anderson, a citizen of the United States, residing at Cranston, in the county of Providence and State of Rhode Island, have invented a new, original, and ornamental Design for a Tie Holder, of which the following is a specification, reference being had to the accompanying drawing, constituting a part thereof.

Fig. 1 is a front elevation of a tie holder, showing my novel design; and

Fig. 2 is a side view thereof.

The essential features of my design are shown in full lines, the particular initials shown in broken lines being merely representative.

I claim:

The ornamental design for a tie holder, substantially as shown and described.

CARL A. ANDERSON.
